J. KÖLLNER

FEEDING BOTTLE FOR INFANTS

Filed May 12, 1927

Inventor:

Josef Köllner
Josef Köllner

att.

UNITED STATES PATENT OFFICE.

JOSEF KÖLLNER, OF SCHAFFHAUSEN, SWITZERLAND.

FEEDING BOTTLE FOR INFANTS.

Application filed May 12, 1927, Serial No. 190,908, and in Switzerland May 18, 1926.

The present invention relates to improvements in feeding bottles for infants and particularly to an arrangement for fixing teats to feeding bottles and has for its object to provide a secure and durable fixation of the teat so that the latter cannot be pulled off the bottle by a tension exerted on the teat.

Arrangements of this type are already known; a constructional example of such arrangements comprises a screw threaded sleeve which is screwed over the teats fitted to the neck of the bottle, the latter being provided with screw thread. This arrangement presents the disadvantage that the teat is injured and torn when the sleeve is screwed on it. Another constructional example comprises a springy ring the ends of which overlap each other and which may be fixed to the neck of the bottle by pressing the two ends towards each other. This ring is disadvantageous inasmuch as it does not tightly press the teat against the neck of the bottle so that liquid from the feeding bottle may escape.

Further it is known to use an elastic rubber ring as a member for holding the teat. This form shows the drawback that after a short use the rubber ring loses its elasticity as it is tensioned and is soon rendered unfit for use. The metal rings provided with locking means which have also been used and which contact directly with the teat cause a quick wear of the latter.

These drawbacks are overcome by the arrangement according to the present invention which shows the feature that a circular ring consisting of a rigid material is used having a U-shaped cross-section open towards its inner side, an elastic insertion being arranged inside the U-shape and intended for pressing the teat against the neck of the bottle.

A construction example of the subject matter of the present invention is illustrated on the accompanying drawings, in which:

Fig. 1 shows the upper part of the neck of a feeding bottle with the means for holding a teat illustrated in section,

Fig. 2 is a horizontal section along line II-II in Fig. 1,

Fig. 3 is a plan view of the clamping ring, and

Fig. 4 shows the whole bottle in elevation.

Fig. 5 shows a detail variation of the neck of the bottle.

In the drawings 1 denotes the feeding bottle the neck 1' of which is provided with a circumferential groove, 2 for receiving the clamping ring 3. The latter is of a U-shaped cross-section open towards the interior and consists preferably of a metal. In the hollow space thus formed an elastic insertion 4 is arranged which may consist of rubber or of a similar material. In order to increase the elasticity the insertion ring 4 is provided with recesses 5.

The teat or mouth piece 7 is pulled through the clamping ring 3, then the latter is pulled over the neck 1' of the bottle 1 until the clamping ring 3 enters the groove 2. Owing to the elastic insertion 4 the teat is tightly pressed against the neck of the bottle and an escape of liquid from the bottle is not possible.

To facilitate the clamping ring 3 together with the teat 7 to be placed on the neck of the bottle the latter is provided with a conical enlargement 8 which joins to the groove 2 and the portion 9 of the neck on the other side of the groove is of a larger diameter than the enlargement 8.

The clamping ring 3 may readily be removed by pulling the ring sideways in several directions and sliding it thereby over the neck.

The circumferential groove 2 in the neck 1' of the bottle 1 may also be omitted as is shown in Fig. 5 in which case the clamping ring is held in position below the enlargement 8'. The end part 10 of the neck is shown to taper slightly inwardly towards the enlargement 8'.

I claim:

1. An arrangement for fixing teats to feeding bottles for infants, comprising a circular ring of a rigid material and having a U-shaped cross-section, the open part of the cross-section pointing towards the inner side of the ring, and an elastic ring inserted in said U-shaped cross-section of the ring and adapted to cause a pressure on the neck of the bottle when pushed over the latter.

2. An arrangement for fixing teats to feeding bottles for infants, comprising a circular ring of a rigid material and having a U-shaped cross-section, the open part of the cross-section pointing towards the inner side of the ring, and an elastic rubber ring in-

serted in said U-shaped cross-section of the ring and adapted to cause a pressure on the neck of the bottle when pushed over the latter.

5. An arrangement for fixing teats to feeding bottles for infants, comprising a circular metallic ring of a U-shaped cross-section, the open part of the cross-section pointing towards the inner side of the 10 ring, and an elastic rubber ring inserted in said U-shaped cross-section of the metallic ring, said rubber ring being provided with recesses for increasing its elastic forces with which it presses towards the neck of the 15 bottle when it is pushed over it.

4. A feeding bottle for infants, comprising in combination, a neck the end part of

which flares slightly inwardly towards an enlargement of said neck, a rubber teat, and a clamping ring for securing said teat to the 20 neck below said enlargement, said clamping ring consisting of a circular metallic ring of a U-shaped cross-section, the open part of the cross-section pointing towards the inner side of the ring, and an elastic rubber ring inserted in said U-shaped cross-section of the metallic ring, said rubber ring being provided with recesses for increasing its elastic forces with which it presses the teat in said 25 groove of the bottle.

In testimony whereof, I have signed my name to this specification.

JOSEF KÖLLNER.
